[57] CLAIM

The ornamental design for a combined anti-rotational bracket and snap-in clip, as shown and described.

DESCRIPTION

FIG. 1 is a left side, top and front perspective view of a combined anti-rotational bracket and snap-in clip, showing our new design;

FIG. 2 is a top plan view thereof;

FIG. 3 is a front elevational view thereof;

FIG. 4 is a right side elevational view thereof the left side elevational view being substantially a mirror image;

FIG. 5 is a rear elevational view thereof; and,

FIG. 6 is a bottom plan view thereof.

FIGS. 2-6 are shown in reduced scale for convenience of illustration and facility of illustration.

FIG. 5

FIG. 4

FIG. 3

FIG. 6
